UNITED STATES PATENT OFFICE.

MALCOLM A. McDONELL, OF CINCINNATI, OHIO.

SEASON-GREETING FRAME.

Application filed March 24, 1928. Serial No. 264,479.

This invention relates to improvements in season greeting frames particularly adapted for use in connection with containers for candies and the like.

5 The object of this invention is to provide a box, container or package constructed in such a manner that it may readily receive in operative relationship therewith a suitably formed frame adapted as a seasonal 10 greeting.

A further object of this invention is to provide a frame for combination with a package or container and constructed in such a manner that the side of the container 15 upon which the frame rests will not be entirely covered, thereby allowing a substantial portion of the top of the container to be clearly visible through the opening in the frame.

20 Another object of this invention is to provide a detachable frame for a container, the periphery of which is adapted to conform with the border structure of the container in such a manner that the frame may 25 be considered an integral part of the container, the frame being detachably connected to the container in such a manner that it may be readily removed therefrom without entirely removing the binding means around 30 the container.

Other objects of this invention will appear in the following detailed description of the device as disclosed in the single sheet of drawings, which is herewith made a part 35 of this application.

In the drawings:

Figure 1 illustrates a perspective view 40 disclosing the top of a container having a specific border structure, and a frame disclosed in detachable relationship thereto for fitting over the border structure.

Figure 2 represents a top plan view of the container, disclosing the frame in assembled relationship therewith, the container and frame being surrounded by a suitable binding element.

Figure 3 represents a sectional view of Figure 2, taken along line 3-3.

Figure 4 illustrates a perspective view of 50 a container disclosing a particular form of this invention wherein the periphery of the container is adapted to receive in assembled relationship therewith a frame having cooperating, downwardly extending tab portions, 55 the frame when in position conforming to the border structure of the container.

Figure 5 illustrates a sectional view of Figure 4, with the frame in assembled relationship therewith.

Figure 6 illustrates a perspective view of a 60 modified form of a frame, according to this invention, disclosing peripheral means for bringing the frame into interlock relationship with the container.

This invention provides a frame adapted 65 for detachably connecting with a suitably formed container such as a box or package, wherein numeral 1 designates the main body portion of a box adapted primarily for holding candy and the like, and having a 70 top portion 2 provided with a border structure 3, which may be of any desirable type such as raised sections integrally formed over the box top 2, or any other desired construction.

In order to retain the original identity of the box top border structure, and at the same time provide the box top with a detachable frame, it is preferred in this invention to construct a frame 4, having its 80 outer periphery 5 to conform in shape and size to the periphery of the container top portion 2, the inner periphery 6, of the frame 4, being formed to suitably coincide with the border portion 3, of the container 85 top portion 2, which will allow a substantial portion of the container top to be visible through the opening in the frame. The container and frame may be held together 90 in detached relationship by any suitable means, such as binding member 7.

Figure 4 represents one form of this invention wherein the detachable frame portion 8 is provided with a plurality of downwardly extending tab elements 9, adapted 95 to cooperate with notched portions 10, in the periphery of the top portion 11 of the container 12; it being understood that the inner periphery 13 of the frame 8 will coincide with the border structure 14 of the container 12, when the two members are brought into interlock and assembled relationship.

Figure 6 represents a further modified 105 form of this invention wherein the numeral 16 designates a detachable frame for use in connection with any suitable container, wherein the outer periphery of the frame 16 is provided with a downwardly extending flange portion 15, and the inner periphery 17 of the frame 16 is adapted to coincide 110 with the border structure of any container

with which the frame 16 is brought into assembled relationship.

This invention provides a detachable frame particularly adapted for use in connection with packages or boxes of candy. The center of the frame is formed with an opening adapted to coincide with the structure of the top of the cooperating package over which the frame is adapted to be placed, in such a manner that the original top or sides of the package may maintain their original identity.

The frame according to this invention is, furthermore, constructed in such a manner that when brought into interlock or assembled relationship with the container top, the inner periphery of the frame will coincide with the border design of the container to the degree that it will appear as an integral part of the container. The frame may be easily removed from the package by releasing the connecting or attaching means.

The device is equally applicable to other containers than for candies, such as cigar boxes, handkerchief boxes, silk stocking boxes, that is the usage of the frame may ex-

tend to all kinds of containers and particularly those which might be called "gift merchandise" boxes.

It is to be understood that alterations and substitutions may be made in the above disclosure both in the specifications and drawings within the scope of the appended claim without affecting the merits of this invention.

What I claim is:

The combination with a package consisting of a box filled with gift articles, having an outer top adapted to be placed over the usual box cover and displaying information relative to some special occasion, said outer top having a section removed whereby the ordinary top will be exposed displaying suitable information to indicate the nature of the gift articles, whereby the package may be sold as a gift package with reference to special occasions with said auxiliary top in place, or as a standard staple package when the auxiliary top is removed.

In testimony whereof I affix my signature.

MALCOLM A. McDONELL.
